PAPER CUTTING AND GRIP-FACILITATING DEVICE

Application filed May 16, 1929, Serial No. 363,538. Renewed September 3, 1931.

This invention relates to a paper cutting and grip-facilitating device adapted primarily for use in mercantile establishments in connection with rolls of wrapping paper 5 although capable of use generally.

It is primarily aimed to provide a means whereby the paper may be unrolled and handled in a sanitary manner and whereby there will be no temptation for the clerk or others 10 to moisten the fingers in order to efficiently and rapidly grip the paper.

In addition, it is aimed to provide a novel means whereby light pressure on a portion 15 will expose a portion of the paper which may be readily gripped and moved forwardly and subsequently cut or torn.

The more specific objects and advantages 20 will become apparent and in part be pointed out, in the description following taken in connection with accompanying drawings illustrating an operative embodiment.

In said drawings:

Figure 1 is a view in front elevation of a 25 roll of paper and its supporting mechanism, having our improvements attached thereto,

Figure 2 is an end elevation of the parts 30 of Figure 1,

Figure 3 is an enlarged detail section taken on the line 3—3 of Figure 1,

Figure 4 is a view similar to Figure 3 but taken through a modified form, and

Figure 5 is a detail section taken on the line 5—5 of Figure 4.

Referring specifically to the drawings, 35 10 designates paper which may be for instance wrapping paper, shown in the form of a roll carried by a roller 11, journaled and supported in a suitable rack or frame 12. Such frame 12 includes a standard 13. The rack

40 or frame 12 is provided with a knife or severing blade 14 across which the paper is drawn in the act of cutting or tearing it from the roll. Such blade or knife 14 has rearwardly extending arms 15 which are pivoted at 16 to

45 the standard 13, the blade 14 thus by gravity normally resting on the roll of paper and moving downwardly automatically as the diameter of the roll decreases. Normally of course the paper 10 is severed by drawing it 50 across the lower edge of the blade or knife

14. This form of support for the paper is to be taken as conventional since it may vary greatly and is shown merely by way of example.

As is well known, it is often difficult to grip 55 the paper beneath the knife 14 in order to pull it forwardly and time is lost and unsanitary moistening of the fingers is resorted to in order to grip and pull the paper forwardly. It is to overcome this inconvenience 60 and unsanitary feature that the present invention has been devised.

Removably bolted as at 17 to the blade 14 are a pair of attaching brackets 18 which have forwardly and upwardly inclined portions 19 with side depending flanges at 20.

A hollow guide and shearing device 21 is disposed forwardly of the blade and extends the full width of the paper so that the latter may be threaded therethrough as shown in 70 the drawings. Integral with the guide is an arm 22 having rearwardly extending flanges 23 pivoted by a bolt or the like as at 24 to the flanges 20, whereby the parts 21, 22 and 23 are movable as a unit and constitute a lever. A leaf spring 25 is fastened as at 26 to the wall 19, passes over the bolt 24 and at its free end engages the arm 22, maintaining the guide device 21 in its foremost position, its movement being limited 75 by the abutment of a stop lug 27 on the arm with the forward end of the wall 19.

As a result of the construction described, when it is desired to grasp the forward edge 80 of the paper 10 and pull it forwardly to unroll a portion thereof, the guide 21 is pressed rearwardly to exert a downward pressure at the lower edge of blade 14 on the paper 10, since the blade swings from the axis 16, thus preventing re-wrapping of the 85 paper and the guide portion 21 will move rearwardly a distance independently of the paper 10 thus exposing a portion thereof in front of the guide device which may be readily gripped by the thumb and forefinger and pulled forwardly, after which the spring 25 restores the guide device to its normal 90 position and the portion of the paper forwardly of the guide device is then severed 95 by elevating the paper and tearing it along 100

the forward edge of the wall of the guide device as at 27', the same thus constituting an auxiliary knife or cutting blade.

It will be understood that various means may be provided whereby the guide device 5 may be mounted to operate according to the principles of my invention in connection with a roll of paper and that it is not limited to the form specifically shown and described.

By way of example, a modified form is shown in Figures 4 and 5 wherein the guide device is designated 28 and is identical with that at 21. The guide device 28 has its arm 29 riveted or otherwise fastened to the free arm 30 of a U-shaped spring 31, and whose other arm is attached by a bolt or otherwise as at 32 to a blade 33 which may be that at 14. The arms 30 and 31 tend to move apart and their separation is limited by a loop 34 surrounding the same. In using this form of the invention, it will be realized that when the guide 28 is pressed rearwardly its rearward movement will be independent of the paper, thus exposing a portion of the same so that it may readily be gripped by the thumb and forefinger and thus function similarly to the device of the other form.

We claim as our invention:—

A device of the class described comprising a lever having a guide device through which material to be fed passes, an attaching bracket to which the guide device is pivoted adjacent the top, said lever and bracket being of U-shape in cross section to provide flanges mounting the pivot connection thereof, a stop member integral with the guide device to abut one end of the bracket to limit the projecting movement of the guide device, and a spring carried by the bracket and engaging the guide device to urge projection thereof, said spring passing over said pivotal connection and being housed in the said flanges.

In testimony whereof we affix our signatures.
